UNITED STATES PATENT OFFICE

PAUL HAYMOND, OF FAIRMONT, WEST VIRGINIA

DEFROSTING APPARATUS

Application filed November 25, 1931. Serial No. 577,334.

This invention relates to mechanical refrigeration and refrigerators and has for its primary object to provide both household and commercial refrigerators of the compressor-condenser-expander type with simplified means by which they will be automatically defrosted at predetermined periods.

One of the greatest, if not the greatest expense in the servicing of mechanical refrigerators is due to the fact that the owners or operators fail to defrost at reasonable intervals and hence allow a very substantial coating of ice to form on the refrigerating coils. This coating or layer of ice not only acts as an insulator and causes a much greater use of power to maintain the refrigerating compartment at the desired temperature, but the continually increasing thickness of the layer causes the partitions to be forced out of shape, disrupts pipe joints and gives rise to many other troubles which require the services of skilled mechanics.

The present invention is designed to render a mechanical refrigerator entirely fool-proof, and the defrosting mechanism disclosed herein is designed to secure the complete defrosting of the coils at each operation, and the defrosting operations are caused to automatically occur at predetermined intervals so that the human element is entirely eliminated. Moreover, the defrosting mechanism is so designed that the slight cost of operation is exceeded many times by the saving in power consumption due to the absence of insulation on the refrigerator coils.

Other objects and advantages of the invention will be in part apparent and in part pointed out in the following detailed description taken in connection with the accompanying drawing, in which,

Figure 1 is a more or less diagrammatic view of a conventional mechanical refrigerator of the flooded type, showing my novel defrosting mechanism incorporated therein, and

Figure 2 is a vertical sectional view, on an enlarged scale, of the reversing valve and its operating mechanism, for permitting a tem-

porary flow of hot gases to the refrigerating coil.

Referring to the drawing in more detail, the numeral 1 indicates a refrigerating cabinet of the usual type, including a horizontal partition 2 which divides the cabinet into a lower compartment 3 for receiving the operating mechanism and an upper refrigerating compartment 4.

Mounted within the lower compartment 3 are the motor 5, compressor 6, condenser 7 and receiver 8. Within the refrigerating compartment 4 is a float-controlled expander 9 including refrigerating coils 10.

A conduit 11 is adapted to convey refrigerant from the receiver 8 to the expander 9 and a conduit 12 serves to return the expanded gases to the compressor 6. The compressed gases are carried from the compressor 6 to the condenser 7 by a conduit 13 which communicates with an extension 14 of the condenser pipe coil. Connected with the pipe extension 14 is a conduit 15 which leads to the interior of the expansion chamber 9.

A valve 16 is located at the juncture of the pipe extension 14 and conduit 15, and serves to normally cut off communication between the high pressure side of the system and the conduit 15. This valve is shown on an enlarged scale in Figure 2 and comprises a plunger 17 carrying a needle valve element 18 which normally rests on valve seat 19. Co-operating with the plunger 17 is a solenoid 20. It will be understood that when the solenoid is energized the plunger will be lifted and the valve consequently opened. Connected in the circuit 21 of the solenoid 20 is a clock 22 provided with a switch (not shown) adapted to be periodically closed and thereby energize the windings of the solenoid.

Also connected in the electrical circuit 21 is a heating coil 23 which surrounds a portion of the conduit 15. This coil it will be understood is energized each time the circuit 21 is closed through the solenoid and serves to heat the gases passing through the conduit 15 to the expander 9.

A conventional connector plug 24 is associated with the circuit 21 and it will of course

be understood that a second circuit (not shown) is also associated with this plug for energizing the electric motor 5.

In operation of the device the time-controlled mechanism is set to close the circuit 21 at the desired time and when the circuit is closed the energized solenoid 20 will lift the needle valve 18 and allow the hot gases from the high-pressure side of the compressor 6 to pass into the conduit 15 and thence to the expander 9. This introduction of hot gases into the expander will, of course, raise its temperature and cause any ice formed thereon and on the coils 10 to melt. The circuit 21 is then again opened and the valve 18 allowed to close. At each operation of the time-controlled mechanism the electrical heating coil 23 is also energized and thus heats the gases passing through the conduit 15 prior to their entrance into the expander 9. Of course if the compressor has not been shut down too long prior to the opening of the valve 16 the gases will be fairly hot, but if the compressor has been shut down for a considerable period of time prior to the operation of the time-controlled mechanism the gases on the high-pressure side of the system will not be sufficiently hot to quickly defrost the refrigerating coils and it is for this reason that the electrical heating coil 23 is provided so as to impart the desired heat energy to the gases under such circumstances.

From the foregoing description taken in connection with the accompanying drawing it will be apparent to those skilled in the art that I have provided an extremely simple and inexpensive construction by means of which hot gases are conveyed to the expander of a refrigerating system at predetermined intervals; that the mechanism is entirely automatic in its operation and that in the event the gases are not sufficiently hot to perform the defrosting operation in the prescribed time interval the electrical heating coil will impart the necessary heat energy to such gases prior to their entrance into the expander.

In accordance with the patent statutes I have described what I now believe to be the preferred form of construction, but it will be apparent that various minor changes may be made in the details of construction without departing from the spirit of the invention and all such changes are intended to be included within the scope of the appended claims.

What I claim is:

1. In a mechanical refrigerator of the compressor-condenser-evaporator type, a conduit leading from the high pressure side of the system to the evaporator, a valve normally closing said conduit, a solenoid for opening said valve, and a time-controlled switch for periodically energizing said solenoid.
2. In a mechanical refrigerator of the com-

pressor-condenser-evaporator type, a conduit leading from the high pressure side of the system to the evaporator, a valve normally closing said conduit, means for periodically opening and closing said valve, and means for heating the conduit.

3. In a mechanical refrigerator of the compressor-condenser-evaporator type, a conduit leading from the high pressure side of the system to the evaporator, a valve normally closing said conduit, an electric heating coil encircling a portion of said conduit, and time-controlled electrical means for periodically opening said valve and energizing said heating coil.

4. In a mechanical refrigerator of the compressor-condenser-evaporator type, a conduit leading from the high pressure side of the system to the evaporator, a valve normally closing said conduit, a solenoid for operating said valve, an electric heating coil encircling a portion of said conduit, an electric circuit in which said solenoid and heating coil are connected, and a time-controlled switch for periodically closing said circuit.
